COMBINATION OF SPARK PLUG AND COMBUSTION CHAMBER HAVING CONNECTED CONICAL AND CYLINDRICAL SECTIONS

The present invention relates to a spark plug for use in a rotary engine.

The spark plug of the rotary engine is detachably mounted in the innermost part of an ignition opening of the rotary engine from the outside. This ignition opening is circular in section and formed in that part of a casing of the rotary engine which serves to compress and ignite a mixed gas by means of a rotor, said casing constituting a combustion chamber therein for the rotary engine.

The ignition opening is designed so that its diameter is made as small as possible so as to prevent a draft of the mixed gas from occurring owing to the pressure difference between adjacent combustion chambers divided by the rotor and that that part of the ignition opening which surrounds the spark discharge electrodes of the spark plug is formed as an inverted conical-shaped funnel for the purpose of facilitating a supply of the mixed gas to the spark gap and also of improving machinability of the ignition opening.

It is desired to locate the spark discharge electrodes as near the combustion chamber as possible so as to improve the thermal property of the spark plug.

In the heretofore known spark plug an outer electrode is mounted on the lower end surface of the metal shell of the spark plug in parallel with a center axis of the shell or perpendicular to the lower end surface of the shell and the free end of the outer electrode is bent at substantially 90° in opposition to a center electrode so as to form a spark discharge gap therebetween. This construction causes the bent portion of the outer electrode to make contact with the conical surface formed at the innermost part of the ignition opening. Thus, it is impossible to locate the spark discharge gap as near the combustion chamber as possible and hence a satisfactory thermal property of the ignition plug could not be obtained.

The principal object of the invention, therefore, is to provide an improved spark plug for use in a rotary engine, which is particularly adapted to locate its spark discharge gap as near the combustion chamber as possible and hence to obtain a satisfactory thermal property.

For a better understanding of the invention, reference is made to the accompanying drawing, in which

FIG. 1 is a front view of a spark plug partially broken away for use in a rotary engine according to the invention;

FIG. 2 is a longitudinal sectional view of essential parts of the elements of FIG. 1; and

FIG. 3 is a longitudinal sectional view of an rotary engine showing the spark plug according to the invention in the mounted state.

Referring to the drawing, 1 designates a metal shell of a spark plug; 2 a ceramic insulator housed in the shell; 3 a center electrode extending through the ceramic insulator 2 and provided at its upper end with a terminal 3a; 4 an outer

electrode projecting from a lower end surface 1a of the shell 1 and arranged in opposition to the lower end face of the center electrode 3 and spaced apart therefrom to form a spark discharge gap G.

5 In accordance with the invention, the outer electrode 4 is mounted at the lower end of the shell 1 so that the outer electrode 4 is projected from the lower end surface 1a of the shell 1 along and spaced apart from an inverted conical surface 5 formed at the upper end of an ignition opening 6 of the rotary engine, the ignition opening 6 being formed in a casing 7 of the rotary engine and in communication with a combustion chamber 8 in which a rotor 9 is rotatably mounted.

As explained hereinbefore, the spark plug for use in the rotary engine according to the invention and comprising the outer electrode mounted on the shell so that the outer electrode is projected along and spaced apart from the conical surface forming the upper end of the ignition opening of the rotary engine so as to minimize the distance from the lower end of the outer electrode to the combustion chamber ensures location of the outer electrode as closely adjacent to the upper conical surface of the ignition opening as possible without requiring any troublesome operation and further provides the important advantage that the spark discharge gap is closely located near the combustion chamber and hence improves the thermal property of the spark plug.

Though the invention is described by means of an embodiment as shown in the drawing, yet various modifications can of course be made without departing from the scope of the claim.

What we claim is:

30 1. For a rotary engine, the combination of a casing having an ignition opening extending to a combustion chamber which is formed in the casing, and a spark plug in said ignition opening, said spark plug including a shell detachably mounted in said ignition opening and having a lower end, an insulated center electrode mounted in said shell, and an outer electrode mounted at said lower end of the shell and projecting into spaced relation with said center electrode to form a spark discharge gap therewith, said ignition opening having a conical surface which narrows in a direction away from said lower end and towards said combustion chamber, said ignition opening having a cylindrical portion extending from said conical surface into said combustion chamber in substantial axial alignment with said center electrode said lower end of the shell being of slightly reduced diameter compared to the remainder of the shell to form a space with said casing which extends into the ignition opening at said conical surface said outer electrode including a portion extending from said lower end substantially parallel to said conical surface in closely spaced relation therewith, the latter portion projecting towards said center electrode.

40 2. The combination as claimed in claim 1 wherein said outer electrode includes a bent portion extending perpendicular to the axis of said center electrode from the first said portion beneath and into opposition to the lower end face of said center electrode.
